UNITED STATES PATENT OFFICE.

WILLIAM E. BELT, OF CHICAGO, ILLINOIS.

SPECTACLES.

SPECIFICATION forming part of Letters Patent No. 625,083, dated May 16, 1899.

Application filed January 23, 1899. Serial No. 703,105. (No model.)

To all whom it may concern:

Be it known that I, WILLIAM E. BELT, a citizen of the United States, residing in Chicago, in the county of Cook and State of Illinois, 5 have invented certain new and useful Improvements in Spectacles, of which the following is a specification.

My invention has for its object an improved frame for securing the lens in spectacles and 10 providing a temple-joint for same. It has heretofore been customary to construct the joint-pieces integral with the bows and connect them with screws, rivets, or the like.

The primary object of my invention is to 15 provide a frame which shall consist of as few parts as possible and be so assembled as to do away entirely with screws, rivets, soldering, &c., and yet have a frame which shall be exceedingly simple in construction, cheap and 20 easy to manufacture, effective, and practically impossible to get out of order. To accomplish this end, I employ a single strip of wire to form the rim, and the bow is bent to form its own fastening at the temple-joint, 25 and other novel features which will be hereinafter more fully explained.

In the drawings, Figure 1 represents a spectacle-frame, showing my improved form of rim and temple-joint. Fig. 2 represents an edge 30 view showing one of the bows open and the other closed. Fig. 3 is an enlarged detail of the temple-joint. Fig. 4 is a view taken on the line 2 2 of Fig. 1. Fig. 5 represents a portion of the rim containing the lens broken 35 away. Fig. 6 is an enlarged detail of the clamp used on the rim. Fig. 7 is a plan view of a section, showing a modified form.

In carrying out the invention, A represents the ends of the wire employed to form the entire 40 rim. It is first bent to conform to the upper half of the lens, then outwardly, then at right angles, and back again to form an ear or projection A', then back to form the lower half of the lens, then gradually curved to form 45 the nose-piece B and continuing around the other lens in the same manner as the first, and, finally, ending on the opposite side of the nose-piece, where it is securely fastened by means of a small clamp b.

C is the wire, which forms the bows and 50 which also is bent to form the temple-joint.

A loop C' is bent in one end of this wire C, and this is passed through the projection A' from the outside and bent once around the wire, forming the projection A'. The wire is 55 then secured by winding tightly around the bow close to the temple-joint.

b² is a clamp which is bent around the projection A to form an abutment for the loop C'. This serves to keep the bows adjusted 60 to the desired position when open and prevents the loop C' from coming into contact with the edge of the lens.

D, Fig. 7, represents another form of my improved spectacle-frame, which is more simple 65 and equally as effective as the one above described. In this I form the entire rim of a single piece of wire, and instead of providing the clamps as shown at b b² in Fig. 1 in bending the wire to form the projection at 70 the outer end of the lens I am able to use the same wire by bending it to form a small loop d within the projection A', which will serve as effectually as an abutment for the temple-joint loop C' as the clamp b². In this form 75 of rim I am enabled to do away with the clamps b also by securing the ends of the eye-wire A simply by tightly coiling them around that portion of the wire between the lower half of the lens and the nose-piece, as shown 80 at d'.

It will thus be seen that I have provided a spectacle-frame which is exceedingly simple in construction and effective in application and have dispensed with all screw-fastenings, 85 rivets, &c., and making it practically impossible for the frame or temple-joint to get out of order. I do not desire to be limited to the specific construction shown in the drawings, as the details thereof might be changed without departing from the spirit of my invention, which consists, essentially, in providing a spectacle-frame composed of a single piece of wire bent in conjunction with the pieces of wire forming the bows to form the temple- 90 joint. 95

Having thus described my invention, what I desire to secure by Letters Patent is—

1. A spectacle-frame having the entire rim formed of a single piece of wire, projecting loops in each end of said rim, an elongated loop on one end of each bow bent around the 5 wire of said projecting loop to form the hinge or temple-joint, substantially as described.

2. In spectacles, the combination of a rim having projecting loops at each end thereof, with a temple-joint consisting of an elongated

loop in one end of each of the bows bent 10 around the wire of said projecting loops, and forming a hinge, substantially as described.

In testimony whereof I hereunto sign this specification in the presence of two witnesses.

WILLIAM E. BELT.
